DESCRIPTION

FIG. 1 is a perspective of a muffler housing showing our new design, the broken lines shown of a engine is for illustrative purposes only and form no part of the claimed design;

FIG. 2 is a right side elevation view thereof;

FIG. 3 is a bottom plan view thereof;

FIG. 4 is a front plan view thereof;

FIG. 5 is a rear plan view thereof;

FIG. 6 is a left side elevation view thereof;

FIG. 7 is a top plan view thereof;

FIG. 8 is a enlarged perspective view of a muffler housing according to our new design;

FIG. 9 is an enlarged right side elevation view thereof;

FIG. 10 is an enlarged bottom plan view thereof;

FIG. 11 is an enlarged front plan view thereof;

FIG. 12 is an enlarged rear plan view thereof;

FIG. 13 is an enlarged left side elevation view thereof; and,

FIG. 14 is an enlarged top plan view thereof; and,

FIG. 15 is a bottom perspective view thereof.

The broken lines shown in FIGS. 8, 10 and 14 are for illustrative purposes only and form no part of the claimed design invention.
